JOURNAL BOX PACKING HOLDER

Clarence L. Carnarius, Peoria, Ill.

Application November 27, 1940, Serial No. 367,451

9 Claims. (Cl. 308—89)

This invention relates to journal boxes and more particularly to a packing holder for use in connection therewith.

The object of the invention is to provide a packing holder of simple and inexpensive construction, by means of which strands or fibers of packing in the journal box are effectually prevented from being carried upwardly by rotation of the journal when the car is in motion and becoming lodged between the journal and journal bearing thereby insuring proper lubrication of the journal and preventing unequal pressure and friction between the journal and bearing which often results in a condition commonly known as a "hot box."

A further object of the invention is to provide a packing holder including a resilient frame adapted to fit within a journal box beneath the journal thereof and provided with oppositely disposed brushes which yieldably engage the journal and prevent strands or fibers of packing from being carried upwardly by rotation of said journal.

A further object is to so construct the brushes that they will have a limited lateral sliding movement with respect to the brush supporting plates so as to compensate for the normal lateral movement between the journal and journal box incident to travel of a car.

A still further object of the invention is generally to improve this class of devices so as to increase their utility, durability and efficiency.

In the accompanying drawings forming a part of this specification and in which similar numerals of reference indicate corresponding parts in all the figures of the drawings:

Figure 1 is a vertical sectional view of a journal box showing the improved packing holder in position thereon.

Figure 2 is a transverse sectional view taken on the line 2—2 of Figure 1, the journal being shown in elevation.

Figure 3 is a vertical sectional view taken on the line 3—3 of Figure 1.

Figure 4 is a top plan view of the resilient frame and its associated parts detached and before being bent into shape, the brushes being shown separated from the supporting plates for sake of clearness, and

Figure 5 is a horizontal sectional view taken on the line 5—5 of Figure 2.

The improved packing holder forming the subject-matter of the present invention may be used in connection with any type or style of journal

box, and in the drawings is shown applied to a journal box of standard construction, in which 5 designates the journal box, 6 the journal and 7 the journal bearing coating therewith. The journal 6 is provided at its forward end with the usual collar 8 and arranged within the box 5 beneath the journal 6 is suitable packing material, indicated at 9. When the journal box is new, the entire surface of the bearing 7 generally contacts with the journal but after being subjected to wear incident to travel of a car, the wear on the parts causes a crevice or space 10 between the lower face of the bearing 7 and the journal. The purpose of the present invention is to prevent fibers or strands of the packing material 9 from being carried upwardly by the rotation of the journal and finding lodgment in this crevice 10 thereby to insure proper lubrication of the journal and at the same time prevent undue friction between the parts which often results in a condition known as a "hot box."

The packing holder comprises a resilient frame 11 preferably formed of spring metal and having its central portion formed with an opening 12 defining oppositely disposed spring arms 13 to permit the body of the frame to be readily bent or flexed into shape so as to fit within the journal box 5 beneath the journal 6 thereof with the side walls of the frame yieldably engaging the inner walls of the journal box to prevent accidental displacement of said frame.

The opposite ends of the frame 11 are solid, as indicated at 14, and the free ends of the portions 14 are bent to form hinge members 15 which coact with correspondingly shaped hinge members 16 formed on the inner ends of brush supporting plates 17, there being pivot pins 18 extending through the hinge members 15 and 16 on each side of the frame so as to permit pivotal movement of the brush supporting plates 17 with respect to said frame. The end portions 14 of the frame 11 are provided with spaced slots 19 and 20 and extending through said slots are flat springs 21, the lower ends of which are riveted at 22 to the end portions 14, while the upper ends thereof extend through the slots 20 and bear against the lower surface of the brush supporting plates 17, as best shown in Figure 1 of the drawings, thereby to normally exert an upward yielding pressure on said plates.

While the specific construction shown contemplates the use of flat springs, it will, of course, be understood that, if desired, coil springs may be employed in lieu thereof with the convolutions of the springs coiled around the pivot pins

18 and with the ends of the springs bearing against the plates 11 to exert an upward yieldable pressure thereon.

Secured to the outer or free ends of the supporting plates 17 are brush members 23 preferably extending the entire width of the frame 11 and which yieldably contact with the journal 6 so as to prevent strands or fibers of the packing material 9 from being carried upwardly by the journal 6 and lodging in the crevice or recess 10. The brush members 23 are slotted or bifurcated at 24 to slidably receive the plates 17, and formed in the outer ends of said plates 17 are spaced slots 25 through which extend bolts, rivets or other similar fastening devices 26 for holding the brush members in position on the pivoted supporting plates 17. It will thus be seen that the brush members 23 are free to slide laterally on the supporting plates 17 so as to compensate for normal lateral movement between the journal and journal box which occurs in the operation of the car. In other words, as the journal moves laterally due to uneven track conditions, curvature and other causes, the journal collar 8 by pressure on the ends of the adjacent brush members 23 will cause said brush members to slide laterally on the supporting plates 17 while at the same time the bolts or rivets 26 extending through the slots 25 will effectually prevent accidental separation of the brush members from their supporting plates.

The rear longitudinal edge of the frame 11 and the rear ends of the plates 17 are formed with projecting portions 26' adapted to be bent laterally on the dotted lines 27 to form inwardly extending rear packing fingers or guards 28 which serve to catch and hold the packing as it tends to rise at the rear of the journal box.

In operation, the opposite ends of the frame 11 are flexed upwardly to a substantially U-shaped position and said frame inserted within the journal box 9. As soon as the pressure on the opposite ends of the frame 11 is released, the end portions 14 of the frame will tend to assume their normal position and thus yieldably engage the inner walls of the journal box and prevent accidental displacement of said frame. When the car is in motion, rotation of the journal 6 will tend to collect and elevate some of the strands or fibers of the packing material 9, but owing to the fact that the brush members 23 engage opposite sides of the journal 6 above the packing material in the box 5, said strands or fibers will be prevented from finding lodgment in the recesses or crevices 10, while at the same time the guard fingers 28 will prevent the packing from rising at the rear of the journal box, thereby insuring proper lubrication of the journal and its associated parts and preventing uneven pressure and friction between the journal and its bearing so as to obviate any tendency to produce what is commonly called a "hot box."

It will, of course, be understood that the packing holders may be made in different sizes and shapes and constructed of any suitable material without departing from the spirit of the invention.

Having thus described the invention, what is claimed as new is:

1. The combination with a journal box adapted to receive packing material and including a journal and bearing therefor, of a packing holder fitting within the box beneath the journal, supporting plates pivotally mounted on the holder and normally held against longitudinal move-

ment with respect to said holder, brushes slidably mounted for lateral movement on the free ends of the supporting plates, and springs secured to the holder and bearing against the supporting plates for normally and yieldably holding the brushes in contact with the journal.

2. The combination with a journal box adapted to receive packing material and including a journal and bearing therefor, of a packing holder fitting within the box beneath the journal and comprising a resilient frame yieldably engaging the inner walls of the journal box, supporting plates pivotally mounted on the opposite ends of the frame and normally held against longitudinal movement with respect to said frame, and yieldably supported brushes slidably mounted for lateral movement on the supporting plates and bearing against the journal.

3. The combination with a journal box adapted to receive packing material and including a journal and bearing therefor, of a packing holder fitting within the box beneath the journal, supporting plates pivotally mounted on the holder and normally held against longitudinal movement with respect to said holder, and yieldably supported brushes bearing against the journal and having a limited lateral sliding movement with respect to said holder.

4. The combination with a journal box adapted to receive packing material and including a journal and bearing having portions thereof spaced from the journal to form crevices, of a packing holder fitting within the box beneath the journal and comprising a resilient substantially U-shaped frame, supporting plates pivotally mounted on the opposite ends of the frame and normally held against longitudinal movement with respect to said frame, and brush members slidably mounted for lateral movement on the free ends of the supporting plates and yieldably engaging the journal for preventing the packing material from being carried upwardly and lodging within said crevices.

5. The combination with a journal box adapted to receive packing material and including a journal and bearing therefor, of a packing holder fitting within the box beneath the journal and comprising a substantially U-shaped resilient frame having spaced sets of vertical slots formed therein, supporting plates pivotally mounted on the opposite ends of the frame and normally held against longitudinal movement with respect to said frame, brushes slidably mounted for lateral movement on the supporting plates and yieldably engaging the journal, and springs extending through the slots in the frame and bearing against the lower faces of the supporting plates.

6. A packing holder for journal boxes comprising a body portion bent to form a substantially U-shaped frame and provided with an opening defining resilient arms, longitudinally slotted supporting plates hingedly connected with the opposite ends of the frame, brushes having bifurcated portions receiving the supporting plates, fastening devices extending through the brushes and slots in the supporting plates, and springs secured to the frame and bearing against said supporting plates.

7. A packing holder for journal boxes comprising a body portion bent to form a substantially U-shaped frame, the opposite ends of said body portion being provided with slots and formed with spaced hinge members, supporting plates having hinge members coacting with the hinge members on the frame, pivot pins extend-

ing through the hinge members, said supporting plates being formed with spaced slots, brushes having their inner ends bifurcated and fitted over the supporting plates, fastening devices extending through the brush members and slots in the supporting plates for permitting lateral movement of the brush members with respect to the supporting plates, and springs each having one end thereof secured to the inner face of the frame and its other end extended through the slots in said frame and bearing against the adjacent supporting plate.

8. The combination with a journal box adapted to receive packing material and including a journal and bearing therefor, of a packing holder fitted within the box beneath the journal, brushes mounted on the holder and yieldably

bearing against the journal, and guard fingers extending laterally from the holder above the packing material at the rear end of said holder.

9. The combination with a journal box adapted to receive packing material and including a journal and bearing therefor, of a packing holder fitted within the box beneath the journal, supporting plates pivotally mounted on the holder, brushes fitted to the free ends of the supporting plates, springs operatively connected with the plates for yieldably supporting the brushes in contact with the journal, and inwardly extending guard fingers carried by the holder and supporting plates respectively and disposed above the packing material at the rear of said holder.

CLARENCE L. CARNARIUS.
